UNITED STATES PATENT OFFICE.

DENNIS C. HESSIAN, OF DETROIT, MICHIGAN.

AUTOMATIC AIR-BRAKE-RELEASING MECHANISM.

Application filed December 18, 1922. Serial No. 607,717.

To all whom it may concern:

Be it known that I, DENNIS C. HESSIAN, a subject of the King of Great Britain and Ireland, residing at Detroit, in the county 5 of Wayne and State of Michigan, have invented certain new and useful Improvements in Automatic Air-Brake-Releasing Mechanism, of which the following is a specification, reference being had therein to the accompanying drawings.

This invention relates to automatic air brake systems and refers particularly to the brake releasing mechanism thereof.

An object of the invention is to provide 15 pneumatically operated means, operable upon failure of the triple valve to work, for automatically actuating the release valve to reduce the pressure of air in the auxiliary reservoir so as to permit the increased or 20 built-up air pressure in the main pipe or conduit to force the mechanism of the triple valve to normal position and permit the air in the brake cylinder to escape, whereupon the brake mechanism will be able to release 25 the brakes.

Another object is to provide simple and effective means for regulating the forward movement of the pneumatically operated means so that the release valve will not be 30 operated until after the triple valve has had an opportunity to operate.

With the above and other objects in view, the invention consists of certain novel features of construction, combination and arrangement of parts, as will be more fully described and particularly pointed out in the appended claims.

In the accompanying drawings:

Figure 1 is a side elevation of the usual 40 brake apparatus of a car having parts broken away and in section and showing my invention applied thereto;

Figure 2 is an enlarged longitudinal sectional view through the auxiliary reservoir 45 and through the cylinder thereon showing the release valve and actuating means therefor in elevation and showing the piston in normal position;

Figure 3 is a view similar to Figure 2 50 but showing the arm extending beyond the rocker of the release valve;

Figure 4 is an enlarged sectional view of the release valve and showing the arm in position to actuate the rocker of the valve;

Figure 5 is a fragmentary top plan view 55 of my invention,

Referring now to the drawings in which like characters of reference designate corresponding parts throughout the several views, the numeral 1 designates a triple valve which may be either a quick action triple valve as shown or a plain triple valve and which controls first, the passage of air under pressure from the main train supply pipe or conduit 2 to an auxiliary reservoir 3; second, the passage of air under pressure from the auxiliary reservoir to the brake cylinder 4 which encloses the brake actuating mechanism, designated generally by the numeral 4'; and third, the passage of air 60 under pressure from the brake cylinder to the atmosphere. The main train pipe 2 receives its supply of air under pressure from a main reservoir (not shown) in communication with suitable air pumps (not shown) 65 and the supply of air to the train pipe is controlled by means of a suitable valve (not shown) which is usually located in the cab of an engine and which also controls the passage of air from the train pipe 2 to the atmosphere. Normally the pressures of air 70 are equal in the train pipe and in the auxiliary reservoir so that as soon as any reduction of pressure is made in the train pipe; as a result of the operation of the valve in 75 the cab to permit the passage of air from the train pipe to the atmosphere or from other causes, the pressure of air in the auxiliary reservoir will be greater than that in the train pipe, consequently the piston 5 and 80 slide 6 of the triple valve will be moved off of their respective seats to permit air from the auxiliary reservoir to pass into the brake cylinder and actuate the brake mechanism 85 to seat the brakes.

The pressure of air in the train pipe will 90 increase or build up rapidly after a reduction of pressure has been made, consequently the piston 5 and slide 6 of the triple valve will be forced to normal position whereupon 95 the air from the brake cylinder will be permitted to escape to the atmosphere and the air under pressure in the train pipe 2 will be permitted to pass into the auxiliary reservoir 3 so that the pressures upon opposite 100 sides of the piston 5 of the triple valve will be equalized.

However, it is known that at various 110 times, due to different causes, the triple valve fails to work so as to permit the air under pressure in the brake cylinder to escape to the atmosphere, consequently, the

brake mechanism will not be able to operate to release the brakes when set. Usually, whenever a triple valve fails to work, a release valve 7 upon the auxiliary reservoir 3 is operated manually to reduce the pressure of air in the auxiliary reservoir, consequently, the built-up pressure in the train pipe will force the triple valve to operate to cut off communication between the auxiliary reservoir and the brake cylinder and to discharge the air from the brake cylinder whereby the brake mechanism will be able to operate.

Considerable damage is apt to occur to the equipment should the brakes of any car of a train be locked and often times trainmen have considerable difficulty in locating the cause of the trouble. This is especially true in so far as long trains are concerned in which case it is necessary for trainmen to walk along the track to get to the car having the locked brakes so as to operate the release valve to bleed the auxiliary reservoir.

With my improved construction, should a triple valve fail to work when it is desired to release the brakes, the pressure of air in the auxiliary reservoir will be reduced automatically, with the result that the brakes can be released. In detail, an auxiliary cylinder 8 is mounted on the auxiliary reservoir 3 and is provided with a stuffing box 9 which surrounds the stem 10 of a piston 11 in the cylinder 8. The outer end of the stem is rigidly secured to a downwardly projecting extension 12 of a horizontal bar 13 slidably mounted on the cylinder 8. A suitable U-shaped bracket 13' is mounted upon the cylinder 8 and is adapted to guide the bar. An arm 14, constructed of spring metal is rigidly secured to the bar at the forward end thereof and is provided with a forwardly and outwardly extending vertical off-set portion 15 which is adapted to engage one side of an arm 16' of the rocker 17 upon the stem 18 of the release valve and to move the said arm 16' inwardly and thereby cause the valve proper 20 to be unseated.

Compressed air is used for moving the piston 11 forward and is conveyed from the train pipe 2 to the rear end of the cylinder 8 by means of a suitable conduit 21. Compressed air is also conveyed from the auxiliary reservoir 3 to the forward end of the cylinder 8 by means of a short conduit 22. In view of the fact the pressures of air in the train pipe and in the auxiliary reservoir normally are equal, it is apparent that the pressures upon opposite sides of the piston 11 normally are equal. However, the conduit 21 is preferably provided with a removable fitting 21' which has a restricted passage 22' for the purpose of retarding the supply of air from the

train pipe to the cylinder 8 so as to give the triple valve an opportunity to work each time it is desired to release the brakes. A coil spring 23, of predetermined weight, is located in the cylinder 8 and is adapted to cooperate with the compressed air admitted through the restricted passage 21' to the cylinder 8 to retard the forward movement of the piston 11 before the brakes are released and to cooperate with the compressed air admitted through the short conduit 22 to return the piston 11 to normal position after the brakes have been released.

When a reduction of pressure is made in the train pipe 2 the pressure of air in the auxiliary reservoir 3 is greater than that in the train pipe, consequently, the piston 11 will remain in its normal position and the piston 5 and cylinder 6 of the triple valve will move to permit air under pressure from the auxiliary reservoir 3 to be admitted to the brake cylinder to actuate the brake mechanism to set the brakes. When the brakes are set, the pressures of air upon opposite sides of the triple valve are equal so that when an increase of pressure is made in the train pipe, the triple valve will usually operate to discharge the air from the brake cylinder and thus permit the brake mechanism to operate so as to release the brakes. When it is desired to release the brakes the built-up or increased pressure of air in the train pipe will be supplied to the cylinder 8 through the conduit 21, but the restricted passage 21' will retard this supply of air so that the triple valve will have a chance to operate in the usual manner under increased pressure from the train pipe 5. Should the triple valve then fail to work, the increased pressure of air will force the piston 11 and bar 13 forwardly which will cause the off-set portion of the arm 14 to move the arm 16 of the rocker 18 and cause the release valve proper 20 to be unseated, whereupon air under pressure in the auxiliary reservoir will be permitted to escape to the atmosphere. The pressure of air in the train pipe will then force the piston 5 and slide 6 of the triple valve to their respective normal positions whereupon the air in the brake cylinder 4 will be able to escape through the triple valve to the atmosphere and the air under pressure in the train pipe will be admitted to the auxiliary reservoir 3 and to the cylinder 8. The piston 11, bar 13 and arm 14 will then be moved to their respective normal positions as a result of the combined force of the spring 23 and air under pressure admitted to the cylinder 8 through the short conduit 22. When the arm 14 is moved rearwardly the off-set portion thereof is adapted to engage the opposite side of the arm 16 and to yield slightly while passing the same.

While it is believed that from the foregoing description, the nature and advantages of the invention will be readily apparent, I desire to have it understood that I do not limit myself to what is herein shown and described, and that such changes may be resorted to when desired, as fall within the scope of what is claimed.

What I claim as my invention is:

- lease valve to bleed said auxiliary reservoir and permit the pressure of air in said conduit to force said triple valve to exhaust the air from said brake cylinder whereby said 5 brake mechanism will be permitted to operate, and means for automatically moving said bar to normal position to permit said release valve to return to normal position.
6. In an air brake system, the combination 10 with a brake cylinder, brake actuating mechanism therein, an auxiliary reservoir for supplying air under pressure to said brake cylinder to operate said mechanism, an air supply conduit, a triple valve for controlling 15 the passage of air from said conduit to said auxiliary reservoir and from said auxiliary reservoir to said brake cylinder, said triple valve also being adapted to exhaust the air from said brake cylinder, a release valve for 20 bleeding said auxiliary reservoir and actuating means for said release valve, of a bar, a member carried by said bar and adapted to engage said actuating means to operate said release valve, guide means for said bar, pneum- 25 matically operated means operable upon failure of said triple valve to work, for automatically actuating said bar and causing said member to operate said release valve to permit the pressure of air in said conduit to 30 force said triple valve to exhaust the air from said brake cylinder whereby said brake mechanism will be permitted to operate.
7. In an air brake system, the combination 35 with a brake cylinder, brake actuating mechanism therein, an auxiliary reservoir for supplying air under pressure to said brake cylinder to operate said mechanism, an air supply conduit, a triple valve for controlling the passage of air from said con- 40 duit to said auxiliary reservoir and from said auxiliary reservoir to said brake cylinder, said triple valve also being adapted to exhaust the air from said brake cylinder, a release valve for bleeding said auxiliary res- 45 ervoir and actuating means for said release valve, of an auxiliary cylinder, a piston in said auxiliary cylinder, a bar connected to said piston, a member carried by said bar and adapted to engage said actuating means 50 to operate said release valve to bleed said auxiliary reservoir, means for supplying air under pressure to said auxiliary cylinder to move said piston and cause said member to operate said release valve to permit the pressure of air in said conduit to force said triple valve to exhaust the air from said 55 brake cylinder whereby said brake mechanism will be permitted to operate.
8. In an air brake system, the combina- 60 tion with a brake cylinder, brake actuating mechanism therein, an auxiliary reservoir for supplying air under pressure to said brake cylinder to operate said mechanism, an air supply conduit, a triple valve for con- 65 trolling the passage of air from said conduit to said auxiliary reservoir and from said auxiliary reservoir to said brake cylinder, said triple valve also being adapted to exhaust the air from said brake cylinder, a release valve upon said auxiliary reservoir, 70 and means for actuating said release valve to bleed said auxiliary reservoir, of an auxiliary cylinder, a piston in said auxiliary cylinder, a bar connected to said piston, a member carried by said bar and adapted to engage said actuating means to operate said release valve to bleed said auxiliary reservoir, means for supplying air under pressure to said auxiliary cylinder to move said piston and cause said member to operate said release valve to permit the pressure of air in said conduit to force said triple valve to exhaust the air from said brake cylinder whereby said brake mechanism will be permitted to operate, and means for retarding the movement of said piston to prevent said member from operating said release valve until after said triple valve has had an opportunity to work.
9. In an air brake system, the combination 90 with a brake cylinder, brake actuating mechanism therein, an auxiliary reservoir for supplying air under pressure to said brake cylinder to operate said mechanism, an air supply conduit, a triple valve for controlling 95 the passage of air from said conduit to said auxiliary reservoir and from said auxiliary reservoir to said brake cylinder, said triple valve also being adapted to exhaust the air from said brake cylinder, a release valve upon said auxiliary reservoir, and means for actuating said release valve to bleed said auxiliary reservoir, of an auxiliary cylinder, a piston in said auxiliary cylinder, a bar connected to said piston, a yieldable 100 member secured to said bar and adapted to engage said actuating means for operating said release valve to bleed said auxiliary reservoir, means for supplying air under pressure to said auxiliary cylinder to move said piston and cause said yieldable member to operate said release valve to permit the pressure of air in said conduit to force said triple valve to cut off the flow of air from said auxiliary reservoir to said brake 105 cylinder and to exhaust the air from said brake cylinder whereby said brake mechanism will be permitted to operate, a connection between said auxiliary reservoir and said auxiliary cylinder for supplying air under pressure from said auxiliary reservoir to said auxiliary cylinder, and yieldable means adapted to co- 110 operate with the air supplied to said auxiliary cylinder through said connection for returning said piston and bar to normal position.
10. In an air brake system, the combina- 115 tion with a brake cylinder, brake actuating mechanism therein, an auxiliary reservoir 120 for supplying air under pressure to said brake cylinder, a piston in said auxiliary cylinder, a bar connected to said piston, a yieldable member secured to said bar and adapted to engage said actuating means for operating said release valve to bleed said auxiliary reservoir, means for supplying air under pressure to said auxiliary cylinder to move said piston and cause said yieldable member to operate said release valve to permit the pressure of air in said conduit to force said triple valve to cut off the flow of air from said auxiliary reservoir to said brake cylinder and to exhaust the air from said brake cylinder whereby said brake mechanism will be permitted to operate, a connection between said auxiliary reservoir and said auxiliary cylinder for supplying air under pressure from said auxiliary reservoir to said auxiliary cylinder, and yieldable means adapted to co- 125 operate with the air supplied to said auxiliary cylinder through said connection for returning said piston and bar to normal position.
11. In an air brake system, the combina- 130 tion with a brake cylinder, brake actuating mechanism therein, an auxiliary reservoir

voir for supplying air under pressure to said brake cylinder to operate said mechanism, an air supply conduit, a triple valve for controlling the passage of air from said conduit to said auxiliary reservoir and from said auxiliary reservoir to said brake cylinder, said triple valve also being adapted to exhaust the air from said brake cylinder, a release valve for bleeding said auxiliary reservoir, and actuating means for said release valve, of an auxiliary cylinder upon said auxiliary reservoir, a piston in said auxiliary cylinder, a bar connected to said piston, a member carried by said bar and adapted to engage said actuating means to operate said release valve to bleed said auxiliary reservoir, a restricted passage for supplying air under pressure from said air supply conduit to one end of said auxiliary cylinder to move said piston and cause said

member to operate said release valve, bleed said auxiliary reservoir and to permit the pressure of air in said conduit to force said triple valve to exhaust the air from said brake cylinder whereby said brake mechanism will be permitted to operate, means for supplying air under pressure from said auxiliary reservoir to said auxiliary cylinder, and yieldable means adapted to cooperate with the air admitted to said auxiliary cylinder through said restricted passage for retarding movement of said piston so as to give the triple valve an opportunity to work before operating said release valve, said yieldable means being also adapted to cooperate with the last-mentioned air supply means for returning said piston to normal position.

In testimony whereof I affix my signature.

DENNIS C. HESSIAN.
